CLAIM

We claim the ornamental design for a hand held controller, as shown and described.

DESCRIPTION

FIG. 1 shows a front perspective view of the hand held controller;

FIG. 2 shows a front view of the hand held controller;
 FIG. 3 shows a rear view of the hand held controller;
 FIG. 4 shows a first side view of the hand held controller;
 FIG. 5 shows a second side view of the hand held controller;
 FIG. 6 shows a bottom view of the hand held controller; and,
 FIG. 7 shows a top view of the hand held controller.
 The portions of the graphical user interface shown in broken lines form no part of the claimed design.
